[57] **CLAIM**

The ornamental design for a combined putting practice device and divot repair tool, as shown and described.

DESCRIPTION

FIG. 1 is a front elevational view of a device for turf correction and for putting practice, showing our new design;

FIG. 2 is a rear elevational view thereof;

FIG. 3 is a top plan view thereof;

FIG. 4 is a bottom plan view thereof;

FIG. 5 is a right side elevational view thereof;

FIG. 6 is a left side elevational view thereof;

FIG. 7 is a top plan view thereof with the fork plates shown in an alternate position; and,

FIG. 8 is a top perspective view of FIG. 7.

The broken line showing of a golf ball is for illustrative purposes only and forms no part of the claimed design.
